UNITED STATES PATENT OFFICE

96,449

DESIGN FOR A TOASTER

Fredrick David Chapman, Evanston, Ill., assignor
to Montgomery Ward & Co., Incorporated,
Chicago, Ill., a corporation of Illinois

Application May 27, 1935, Serial No. 57,045

Term of patent 7 years

To all whom it may concern:

Be it known that I, Fredrick David Chapman, a citizen of the United States, residing at Evanston, in the county of Cook and State of Illinois, have invented a new, original, and ornamental Design for a Toaster, of which the following is a specification, reference being had to the accompanying drawing, forming a part hereof.

In the drawing, the figure is a perspective view of a toaster showing my new design, the reverse side of the toaster having the same appearance as the obverse thereof.

I claim:

The ornamental design for a toaster, as shown and described.

FREDRICK DAVID CHAPMAN.
